UNITED STATES PATENT OFFICE.

EMBURY MCLEAN, OF BROOKLYN, NEW YORK, ASSIGNOR TO THE ENGINEER COMPANY, OF NEW YORK, N. Y., A CORPORATION OF NEW YORK.

BAFFLE-RETAINING FORM.

1,319,528.

Specification of Letters Patent.

Patented Oct. 21, 1919.

Application filed March 3, 1919. Serial No. 280,281.

To all whom it may concern:

Be it known that I, EMBURY MCLEAN, a citizen of the United States, residing in New York city, borough of Brooklyn, in the county of Kings and State of New York, have invented certain new and useful Improvements in Baffle-Retaining Forms, of which the following is a specification.

As is well understood, steam boilers of the water tube type are commonly provided with baffles extending across the boiler tubes for directing the gases in a plurality of passes over the tubes. Such baffles may be made, in whole or in part, of a plastic material, such as fireclay cement or asbestos. When such material is used for the baffle, a retaining form of some kind must be used for giving the proper form to the baffle while it is being prepared, and for maintaining the same in position until the material is set. Hitherto such forms have commonly been made of boards, the use of which, however, requires the expenditure of a good deal of time for fitting the boards around the boiler tubes, and the difficulty is increased when some of the tubes are sprung out of position.

In accordance with my invention, retaining forms having flexible wings are used, the wings being provided with recesses adapted to receive the boiler tubes, the flexible wings readily bending around the tubes to conform to the contour thereof in case of a slight misfit. Standard forms for a given type of boiler may thus be used.

My invention will best be understood by reference to the accompanying drawing, in which Figure 1 is a side elevation, partially in section, illustrating a steam boiler of the water tube type, to which my invention is applied; Fig. 2 is a perspective view, with certain parts in section, of a baffle extending across the water tubes, and a retaining form made in accordance with my invention adjacent to the baffle; Fig. 3 is a detailed view of a retaining form for use with an inclined baffle; and Fig. 4 is a similar view for use with a vertical baffle.

Referring, now, to the drawing, in which like reference characters indicate like parts, 1 is the setting of the steam boiler, and 2 a steam and water drum disposed above the same. A bank of horizontally inclined water tubes 3 are connected at one end to a

downtake header 4, and at the other end to an uptake header 5, the headers being nippled to the boiler at 4' and 5', respectively. In the boiler illustrated, a bridge wall 6 is located beneath the water tubes and a baffle, indicated in general by the reference numeral 7, extends from the top of the bridge wall 6 and is inclined rearwardly across the tubes 3. The baffle 7 is formed, in whole or in part, of plastic material, such as cement, and is here illustrated as formed in part of rows of fire bricks 8 and partially of plastic material 9, the plastic material being filled in between the rows of fire bricks.

Now, in accordance with my invention, forms composed of sections against which the plastic material of the baffle wall may be formed and which retain the baffle wall when so formed in position until the plastic material is set are provided, the sections of the form being indicated in general by the reference character 10, each of which sections comprises a substantially straight rigid member 11, to which are secured wings 12 of flexible material, such as thin sheet metal, formed at their edges with recesses 13, which are preferably oval shaped, as shown in Fig. 3, when the retaining form is to be used with an inclined baffle, such as that shown as extending upwardly from the bridge wall in Fig. 1. The form is inserted between the boiler tubes flatwise and is then turned on edge, the boiler tubes being received in the openings 13 and the edges of the wings surrounding the boiler tubes readily bending around the tubes, thus causing the wings to conform to the contour of the boiler tubes. The edges of the sections meet and thus provide a continuous form.

When the retaining form is to be used with a baffle disposed in a plane approximately at right angles to the length of the tubes, such as that shown depending from the wall in Fig. 1 at 7', the recesses in the wings of the retaining form are preferably substantially semi-circular, as indicated in Fig. 4 at 13'.

In forming a baffle against a form made in accordance with my invention, it will be understood that the rows of fire tiles which are to be used in the baffles will first be inserted between the rows of boiler tubes, in the position to be occupied by the finished baffle. The sectional form made in accord-

ance with my invention will then be placed against the rows of bricks and the plastic material will be filled in between the rows of bricks and the boiler tubes to complete the 5 baffle. Ordinarily it will be necessary to use a form on only one side of the baffle, as indicated in Fig. 1, particularly when the baffle is inclined as there shown, though it will, of course, be understood that a form 10 may be inserted on the other side of the baffle to retain the same in proper position until the baffle is set, if so desired.

While I have herein shown and described one modification of my invention, I do not 15 desire to be limited to the exact arrangement shown and described, but seek to cover in the appended claims all those modifications which come within the true spirit and scope of my invention.

20 What I claim and desire to secure by Letters Patent of the United States is:

1. A baffle retaining form comprising a straight rigid member having flexible wings,

said wings being formed with recesses for the reception of boiler tubes.

2. A baffle retaining form comprising a straight rigid member having flexible wings, 25 said wings being formed with curved recesses.

3. A baffle retaining form comprising a straight rigid member having flexible wings of sheet metal, said wings being formed with intervening recesses.

4. A baffle retaining form comprising a rigid member having flexible projecting wings formed with recesses adapted to receive boiler tubes upon which a baffle is to be built, the form being adapted to be inserted between the boiler tubes.

In testimony whereof, I have hereunto 40 signed my name in the presence of two subscribing witnesses.

EMBURY McLEAN.
